UNITED STATES PATENT OFFICE.

JOHN F. MUZIK, OF BUFFALO, NEW YORK.

AEROPLANE.

Application filed May 7, 1921. Serial No. 467,551.

To all whom it may concern:

Be it known that I, JOHN F. MUZIK, a citizen of the United States, residing at Buffalo, in the county of Erie and State of New York, have invented certain new and useful Improvements in Aeroplanes, of which the following is a specification.

My invention contemplates the production of a new and improved aeroplane, and 10 it has for one of its objects the provision of means for increasing the lifting power of the lifting planes.

It further has for its object the provision of means applied to the lifting planes 15 whereby the lifting power of said planes are increased, whereby increased speed is assured, and at the same time complete stabilization of the aeroplane.

A still further object of my invention is 20 to provide an aeroplane in which the respective air-impinging surfaces are relatively arranged in an improved manner, assuring greater speed and power, and to position the propeller and power medium in 25 a new and novel manner.

With the above and other objects in view, the invention consists in the novel construction, arrangement and combination of parts 30 to be hereinafter described and more particularly pointed out in the subjoined claims.

In the drawings:—

Fig. 1 is a side elevation of an aeroplane embodying the various features of my invention in what I now consider its preferred form.

Fig. 2 is a plan view of a portion of the aeroplane.

Fig. 3 is a front elevation of the same.

40 Fig. 4 is an enlarged longitudinal section taken on line 4—4, Fig. 3.

Fig. 5 is an enlarged transverse section taken on line 5—5, Fig. 2.

45 Fig. 6 is a longitudinal section taken on line 6—6, Fig. 5, looking in the direction of the arrow crossing said line.

Fig. 7 is a plan view of a portion of one of the lifting planes, showing a modified form of air-controlling wings thereon.

50 Fig. 8 is a front edge view of the plane shown in Fig. 7.

Fig. 9 is a plan view of a portion of one of the lifting planes, showing a still further modified form of air-controlling wings 55 thereon.

Fig. 10 is an edge view of the plane shown in Fig. 9.

Fig. 11 is a plan view of one of the lifting planes, with a still further modified form of air-controlling wings thereon.

Fig. 12 is a front edge view of the lifting plane shown in Fig. 11.

My improved aeroplane is shown in the drawings as having a car or passenger housing and three sets of planes, and although the plane so constructed is believed to be highly efficient in action, it is not my intention to limit myself to an aeroplane of this type, as certain features of my invention may be embodied in any kind of aeroplane, hydroplane, or other types of flying machine.

The reference numeral 15 designates the car or body of the aeroplane designed to accommodate a number of passengers; the car or body being provided with a door 16 and windows 17. The car or body is supported on wheels 18 rotatable on axles supported by a suitable framework 19 extending from the car or body 15. It is of course to be understood that a body or fuselage of boat-form or any other desired form may be substituted for the car or body shown. The walls of the car or body are of course built around a suitable frame or structure, which may be varied and forms no part of my invention.

However, rising from the car or body, or from the frame-work of said car or body, are uprights 20, three sets of uprights being employed in the particular form of aeroplane shown, each set comprising four uprights and two of each set being arranged at each side of the car or body and extending upwardly therefrom.

The uprights rising from each side of the body are connected together by longitudinal beams or members 21, 22, the longitudinal beams or members 21 connecting the upper ends of the uprights, while the longitudinal beams or members 22 connect said uprights together at a suitable point between the beams or members 21 and the car or body, said longitudinal beams or members 22 being, however, preferably arranged close to the car or body.

100 The longitudinal beams or members at opposite sides of the longitudinal center of the aeroplane are connected together at the front by transverse end beams 23, and at the rear by similar end beams 24, and at suit-

105

110

able points between the transverse end beams 23, 24, intermediate transverse connector beams 25 are connected to said longitudinal beams or members, thus providing a 5 rigid superposed frame supported by the car or body and adapted to carry the lifting planes and other parts of the aeroplane, to be hereinafter described.

26, 27 and 28 designate three sets of lifting or sustaining planes, each set comprising four planes 29, 30, 31 and 32 arranged in pairs at each side of the superposed frame, the plane 29 of each set being above and paired with the plane 31 and the plane 15 30 being above and paired with the plane 32. Said planes extending laterally from the superposed frame, in opposite directions, the two pairs of each set being spaced apart directly above the car or body 15. The 20 two pairs of planes of each set may be referred to as bi-planes spaced apart in the usual manner, the upper planes 29 and 30 being supported from the lower planes 31 and 32 by means of struts 33.

25 One set of lifting or sustaining planes is arranged at or near the front end of the car or body, a second set at or near the rear end thereof, and the third set centrally between the first and second sets. These lifting or sustaining planes may be constructed in any approved manner, the two upper planes of each set being secured to or including in their construction, spars 34 which extend transversely across the aeroplane, and are secured to or constructed with the frame-work of the lifting or sustaining planes in the usual way, alined planes of each set at opposite sides of the car or body having two spars which are secured 30 to the longitudinal beams or members 21 or 22 of the superposed frame by means of clips 35, or otherwise, the rear spar of each two alined planes being secured to the bottom of one of the longitudinal beams while 35 the front spar is secured to the top of said beam, as clearly shown in Fig. 4.

50 The lifting or sustaining planes have the usual outline; that is, they are convex on the upper side and concave at the lower side, and by arranging the spars at the front of the planes above the longitudinal beams or members 21 or 22, as the case may be, and the spars at the rear below said beams or members, the planes are given a proper 55 angle of incidence. It is of course understood that the planes may be otherwise secured to the superposed frame and still have the spars thereof positioned to provide planes with the proper angle of incidence, 60 but I consider the arrangement and construction described to be simple, inexpensive, and highly efficient.

65 Each of the lifting or sustaining planes is provided with one or more air-controlling wings 36 which extend from the upper con-

vex surface of the plane and also from the lower concave surface thereof. These wings range from the front to the rear edge of the lifting planes, and in preferred form, each is curved so as to have an inner concave 70 and an outer convex surface, as best shown in Fig. 2, the wings being arranged parallel and set obliquely lengthwise so that the front end thereof is farther from the longitudinal center of the aeroplane than the rear end, each wing having preferably the same camber and chord as the main wings, and also the same angle of incidence. They are also preferably set at an angle or inclined inwardly toward their upper ends, 75 and each comprises a suitable frame-work 80 supported on sleeves 38 having obliquely-disposed flanges 39, the angle of the flanges determining the angle at which the air-controlling wings are disposed, due to the fact 85 that the frame-work 37 of each of said wings is forced against the flange or flanges of the associated sleeves, as clearly shown in Fig. 5. The flanged sleeves 38 are pinned or otherwise secured to the spars 34 extending 90 lengthwise through the lifting or sustaining planes and the air-controlling wings are maintained rigidly on the lifting or sustaining planes by means of wires 40.

95 The air currents passing under and over the lifting or sustaining planes come in contact with the inner sides of the wings 36 and are broken up thereby. In this manner, cross currents of air are created which produce a forward thrust and a lifting effect 100 on said wings, thus giving the aeroplane greater forward thrust and consequently more speed and also more lifting power. By curving said wings and thereby creating an angle of incidence conforming to the 105 angle of incidence of the lifting planes from which they project, and by arranging said wings at an angle transversely, side slip of the currents of air on the lifting planes is prevented. Moreover, said wings act as 110 stabilizing means, since the cross currents of air created by the air currents coming in contact with the wings 36 are forced toward the center of the aeroplane within and above the superposed frame, which frame 115 provides a substantially open space except at the point where the elevating planes and rudders, to be presently described, are arranged.

120 In the open space within the superposed frame, which extends the full length of the aeroplane, two elevators 41, 42 and two rudders 43, 44 are arranged; the elevator 41 being positioned between the two pairs of lifting or sustaining planes at the front and 125 the second elevator 42 being positioned between the two pairs of lifting planes at the rear, while the rudder 43 is arranged at the extreme front end of the superposed frame directly in advance of the elevator 41 and 130

the rudder 44 is arranged at the extreme rear of the frame directly in rear of the elevator 42.

Each of the elevators is pivotally attached

- 5 to two opposite uprights 20, as at 45, at points closer to their front ends than their rear ends, and they are adapted to be operated in any approved manner, the operation thereof causing the front ends to be raised 70 or lowered, depending upon whether the aeroplane is to ascend or descend. As elevators for aeroplanes are not broadly new, various means are in common use for operating the same. I, therefore, have not considered it necessary to disclose any means 75 for this purpose, and it is apparent that they may be operated independently or in unison, as may be desired.

Each of the elevators has wings 46, which 20 extend upwardly and downwardly therefrom, these wings being arranged at a slight angle to the longitudinal center of the elevator so that during the forward movement of the aeroplane the air currents will impinge thereagainst. These wings differ from 25 the wings of the lifting or sustaining planes in that they are arranged vertically or in perpendicular position, with their rear ends closer to the longitudinal center of the elevator than their front ends. The angle of 30 incidence of said wings thus formed serves to prevent currents of air passing over or under the elevators, as the case may be, sideways, thus giving the elevators more power 35 and assuring a quicker ascent or descent.

Each of the rudders is provided at opposite sides with wings 47 having a slight angle of incidence, the front ends of the wings sloping downward rearwardly so that 40 the air currents coming in contact with the rudders will have a greater gripping or impinging effect thereagainst, thus giving the rudders more power and making them more responsive so as to cause the aeroplane to be 45 directed in a circular path with greater speed. The elevators 41 and 42 and the rudders 43 and 44 may be considered broadly as directional means, each of the members 50 forming said directional means having air-controlling wings thereon, for the purposes stated.

I have illustrated in the drawings four propellers 48, one of which is arranged in rear of each pair of the front and intermediate set of lifting or sustaining planes, these propellers being secured on shafts 49 supported in any suitable manner and driven from motors (not shown) arranged, if desired, in rear of each pair of lifting or sustaining planes of the front and intermediate sets, or within the car or body 15 with suitable transmission means from the motors to the propeller shafts. As the particular manner of supporting and positioning the 60 motors forms no part of my invention, I do 65

not deem it necessary to illustrate the same; and furthermore, the propellers arranged as described may be operated in any approved manner.

In Figs. 7 and 8 I have shown a modified 70 form of air-controlling wing 50 applied to a lifting or sustaining plane. In this instance each of the wings extends above and beneath the plane, is curved and co-extensive with the width of said plane and arranged at a slight angle lengthwise to provide an angle of incidence for the air currents. The wings, in this modification, are arranged vertically or perpendicular and they have 75 preferably the same camber, chord, and angle of incidence as the lifting or sustaining plane from which they extend. While they do not in any manner serve to increase in the lifting action of the lifting planes, they nevertheless act in other respects similar to 80 the preferred construction of wings shown in the preceding figures of the drawings; that is, they will give the lifting wings a greater forward thrust and consequently increase the speed of the aeroplane. They also act to break up the air currents passing over and under the lifting or sustaining planes and create cross currents of air and direct them toward the open center of the aeroplane, thus giving a stabilizing effect. 85

In Figs. 9 and 10 another modification of controlling wing is shown applied to a lifting or sustaining plane. These wings are the same in all respects as the preferred 90 form of wing shown in Figs. 1 to 6, with the exception that each wing, designated by the numeral 51, is flat and not curved as in the main construction. This construction and arrangement of wing increases the speed 95 of the aeroplane and assists in the lifting power of the lifting or sustaining planes, at the same time serving as stabilizing means. 100

In Figs. 11 and 12 I have shown air-controlling wings 52, which are arranged at an angle transversely, but are disposed in a straight line from front to rear of the lifting or sustaining plane, from which they project; the wings thus being parallel with the longitudinal center of the plane. Wings so constructed will increase the lifting or 105 sustaining power of the lifting planes and also act as stabilizing means. 110

While I have illustrated an aeroplane having a plurality of sets of lifting or sustaining planes, it will be apparent that my improved air-controlling wings may be applied to the lifting wing or sustaining plane of a monoplane, or to the planes of a bi-plane, or any other type of aeroplane; also that the air-controlling wings may be applied to elevators and rudder arranged in a manner different than herein shown and described, as the effect of the air currents thereon will be the same in all 115 cases. 120

Where in the appended claims the word "fuselage" is employed, it is intended to mean a car or body of the type shown in the drawings, or any other form of housing or support adapted for use on land or sea.

Having thus described my invention, what I claim is:-

1. An aeroplane having a plane provided with a convex upper surface and a concave lower surface, and air-controlling wings ranging from the front to the rear edge of said plane, said air-controlling wings having the same camber, chord and angle of incidence as said lifting planes.
- 10 2. An aeroplane having a plane provided with a convex upper surface and a concave lower surface, and air-controlling wings ranging from the front to the rear edge of said plane, said air-controlling wings having the same camber, chord and angle of incidence as said lifting planes.
- 15 3. An aeroplane having a plane provided with transverse wings arranged diagonally and at an angle to the surface thereof and serving to prevent side slipping of the under and over currents of air on said plane.

incidence as said lifting planes and being arranged at an angle transversely.

3. An aeroplane having a plane provided with cross wings disposed transversely thereon and arranged diagonally and at an angle to the surface of said plane, said wings serving to break up the currents of air which flow under and over said plane and creating cross currents of air which produce a forward thrust and lift on said wings so as to give the plane more forward thrust, greater lifting power and more speed.

4. An aeroplane having a plane provided with transverse wings arranged diagonally and at an angle to the surface thereof and serving to prevent side slipping of the under and over currents of air on said plane.

In testimony whereof I affix my signature.

JOHN F. MUZIK.
